(57) CLAIM

We claim the ornamental design for a pet brush, as shown and described.

DESCRIPTION

FIG. 1 is a perspective view of a pet brush showing my new design;

FIG. 2 is a left-side view of the pet brush showing in FIG. 1;

FIG. 3 is a right-side view of the pet brush showing in FIG. 1;

FIG. 4 is a back-side view of the pet brush showing in FIG. 1;

FIG. 5 is front side view of the pet brush showing in FIG. 1;

FIG. 6 is a top side view of the pet brush showing in FIG. 1; and,

FIG. 7 is a bottom side view of the pet brush showing in FIG. 1.

The broken lines illustrate environmental structure that forms no part of the claimed design.
